UNITED STATES PATENT OFFICE

2,504,410

BENCH VISE FOR SAW FILERS

Henry C. Hancock, San Antonio, Tex.

Application October 17, 1947, Serial No. 780,406

1 Claim. (Cl. 76—78)

1

My invention relates to improvements in bench vises for holding saws for filing, the primary object in view being to provide a simply constructed, strong, light weight vise adapted for easy, quick attachment to a work bench to hold hand saw blades rigidly throughout the length thereof for filing purposes, and which is equally well adapted for holding band saws for the same purpose.

Another object is to provide a device of the character and for the purpose above set forth which is especially adapted for clamping hand saw blades uniformly and against slipping throughout the length thereof and preventing vibration of the saw blades during filing.

Other and subordinate objects, within the purview of my invention, together with the precise nature of my improvements will be readily understood when the succeeding description and claim are read with reference to the drawings accompanying and forming part of this specification.

In said drawings:

Figure 1 is a view in front elevation of my improved bench vise in a preferred embodiment thereof attached to a work bench and with a hand saw blade clamped therein;

Figure 2 is a fragmentary view in plan;

Figure 3 is a view in transverse section taken on the line 3—3 of Figure 1;

Figure 4 is a fragmentary view in perspective of one of the U-shaped frame members and the channel tie bar drawn to a larger scale;

Figure 5 is a detail view in transverse section taken on the line 5—5 of Figure 1 and drawn to a larger scale;

Figure 6 is a fragmentary view in perspective of the movable clamping bar.

Referring now to the drawings by numerals, according to my invention, as illustrated, a bench vise is provided comprising a plurality, preferably three, of U-shaped T iron frame members 1 having relatively short and long front and rear legs, 2, 3, the rear legs 3 having rearwardly extending, preferably flat, clamping bars 4 welded at one end thereof, as at 5, on the ends thereof at a right angle thereto, and similarly extending similar bars 6 welded at one end, as at 7, thereto at a suitable distance from said bars 4 so that said bars 4, 6 form pairs on said members 1 adapted to straddle the front edge of a work bench 8. A channel tie bar 9 suitably fixed in said members 1, adjacent the bight ends thereof, connects said members together in equidistantly spaced relation to form a frame slightly shorter than the usual hand saw blade. Hand screws

2

10 threaded through the bars 6 with swivel clamping heads 11 thereon form together with said clamping bars 4, clamps on the rear of said members 1 for securing the said frame to the front edge of the work bench 8 with said members 1 depending vertically open ends uppermost.

A pair of opposed, relatively fixed and movable, front and rear, angle iron clamping bars 12, 13, with channel sides facing, are provided for clamping the blade 14 of a hand saw in the described frame, said clamping bars 12, 13 being at least as long as the usual hand saw blade and adapted to clampingly engage opposite sides of said blade along the same.

15 The fixed clamping bar 12 is welded at its rear convex side, adjacent its apex corner, to the front ends of the clamping bars 4, as at 15, said ends of the clamping bars 4 being beveled, as at 16, so that said bar 12 is disposed with its edges arranged in a plane lying between the front and rear legs 2, 3 of said members 1 parallel therewith.

16 The movable clamping bar 13 is fixed, in the same manner as said bar 12, to the upper ends of clamping levers 17 pivoted adjacent said upper ends thereof, as at 18, to the upper ends of the front legs 2 for rocking in opposite directions to move the movable clamping bars 13 toward and away from the fixed clamping bar 12 into and from clamping relation thereto, respectively.

20 The pivots 19 of the clamping levers 17 are arranged to provide on said levers short upper lever arms 19 above said pivots 18 and carrying said bar 13, and long lever arms 20 below said pivots 18 curving downwardly and forwardly relative to said frame.

25 A bail-like yoke 21 is provided for rocking the clamping levers 17 in unison comprising bars 22 upstanding from the front legs 2 of said members 1 with lower ends pivoted as at 23, to the front legs 2, and upper ends connected by a channel bar 24, the arrangement being such that the yoke 21 is swingable rearwardly and forwardly toward and from the described frame. Pins 25 on said bars 22 riding in arcuate slots 26 in the long 30 lever arms 20 of the clamping levers 17 operatively connect the yoke 21 to said levers 17 so that forward swinging of the yoke 21 rocks said levers 17 in a direction to move the movable clamping bar 13 into clamping relation to the fixed clamping bar 12, and swinging of said yoke 21 rearwardly rocks said levers 17 in the opposite direction to move the movable clamping bars 13 out of clamping relation to the fixed clamping bar 12. 35 The curve of the slots 26, it will be noted, is such that, when the yoke 21 is swung forwardly,

for instance into substantially the dotted line position shown in Figure 3, the pins 25 will bind in said slots 26 and frictionally lock the movable clamping bar 13 in clamping relation to the fixed clamping bar 12.

A particular feature of my invention is that the fixed and movable clamping bars 12, 13 are provided with upstanding upper side edge flanges 27 for clamping stretches of a band saw, not shown, therebetween.

Another particular feature of my invention is a cushion strip of triangular cross section and resilient material, such as rubber, and which, as shown at 28, is fitted in the channel of the movable clamping bar 13 and projects slightly out of the same to engage one side of the saw blade 14 flat and prevent the same from vibrating during filing when said blade is clamped between said bars 12, 13.

The use and operation of the described vise will be readily understood. To clamp the saw blade 14 in the vise, the channel bar 24 of the yoke 21 is grasped and shoved rearwardly from the full line position shown in Figures 2 and 3, toward the described frame. This causes the clamping levers 17 to be rocked clockwise as viewed in Figure 3 to move the movable clamping bar 13 away from the fixed clamping bar 12. The saw blade 14 is then positioned between said clamping bars 12, 13, after which the channel bar 24 of the yoke 21 may be pulled rearwardly, away from said frame 1, yoke 21 into the dotted line position shown in Figure 3. This causes the movable clamping bar 13 to be moved so as to clamp the saw blade 14 between the same and the fixed clamping bar 12, in a manner which will be clear. When so clamped, the side edges of the clamping bars 12, 13 engage the sides of the saw blade 14 along two parallel longitudinal lines upon each side of said blade, thereby securing the same in rigid position. The cushion strip 28 is compressed and prevents the saw blade from vibrating during filing in a manner which will be clear.

The foregoing will, it is believed, suffice to impart a clear understanding of my invention, without further explanation.

Manifestly, the invention, as described, is sus-

ceptible of modification without departing from the inventive concept, and right is herein reserved to such modifications as fall within the scope of the appended claim.

Having described the invention, what is claimed as new is:

A vise for attachment to a work bench to hold a saw blade for filing comprising an elongated frame, pairs of cooperating clamping devices spaced along said frame for securing the same to one edge of said bench to depend from said edge, a pair of angle iron clamping bars opposed with channel sides facing and adapted to extend along opposite sides of a saw blade interposed between the same to clamp said blade between the side edges of said bars, one of said bars being fixed on top of said frame to extend along the same, the other clamping bar being movable, vertical levers pivoted on said frame in laterally spaced relation with ends fixed to the movable clamping bar at points spaced along the same and swingable to move said movable bar into clamping relation to said fixed bar, and means for swinging said levers in unison, comprising a yoke pivoted on said frame for vertical swinging downwardly and forwardly of said frame, said yoke having pins thereon and said levers having vertically curved slots therein in which said pins slide and bind to frictionally lock said movable clamping bar in clamping relation, said movable clamping bar having a resilient cushion strip therein for compression against one side of the blade to prevent the blade from vibrating during filing between said clamping bars.

HENRY C. HANCOCK.
